Henry W. Plester, ^{INVENTOR}

BY
Alan W. Johnson
ATTORNEY

UNITED STATES PATENT OFFICE.

HENRY W. PLEISTER, OF WESTFIELD, NEW JERSEY, ASSIGNOR TO HENRY B. NEWHALL, JR., EXECUTOR OF HENRY B. NEWHALL, DECEASED.

BOLT-ANCHOR.

1,288,177.

Specification of Letters Patent.

Patented Dec. 17, 1918.

Application filed May 4, 1918. Serial No. 232,472.

To all whom it may concern:

Be it known that I, HENRY W. PLEISTER, a citizen of the United States, residing at Westfield, in the county of Union and State 5 of New Jersey, have invented certain new and useful Improvements in Bolt-Anchors, of which the following is a specification, taken in connection with the accompanying drawings.

10 My invention relates to bolt anchors.

In the present form of bolt anchors now on the market, the maximum expansion is approximately at the extreme inner end of the an hor. In practice this often is a 15 serious detriment in that the screw or other expanding member, having forced the bolt anchor out to its maximum expansion, binds and it is impossible to bring the head of the bolt up flush with the work. This requires 20 that the hole be enlarged, entailing additional labor and expense, or a different size bolt anchor be used.

By my present invention I not only obtain a bolt anchor of greater flexibility and 25 lighter weight, thereby saving material, but also overcome the objection above noted, giving a longer surface of maximum contact or grip on the exterior of the bolt anchor, thereby insuring an increased frictional hold, and distributing this maximum 30 grip over a larger area.

Further, by my invention, in case the hole is drilled too tight, or not of quite the correct diameter to accommodate the full expansion of the bolt an hor, the highest set of 35 ribs, at the inner end of my bolt anchor, will more or less bend or collapse. This eases the torsional strain on the head of the bolt or screw and permits the bolt being screwed 40 home without either jamming or having its head twisted off.

My present bolt anchor gives greater rigidity of the body member or shell where the axial bore tapers and where the expansion is produced.

My invention further relates to certain details of construction and combinations which will be more fully hereinafter described and set forth in the appended claims.

50 I have shown in the accompanying drawing different illustrative embodiments of my invention, but of course it is to be understood that my invention is not to be confined to the forms illustrated except as re-

quired by the scope of the appended claims. 55 In this drawing, the same reference numerals refer to similar parts in the several figures.

Figure 1 is a vertical section through a two-part bolt anchor, known as a two-part 60 lag shield, embodying my invention.

Fig. 2 is a vertical section through the lag shield shown in Fig. 1, mounted in a support and coöperating with a lag screw and with the work to be supported.

65 Fig. 3 is a vertical section similar to Fig. 2, but showing the hole in the support drilled too tight to accommodate the full expansion of the bolt anchor without the bending or collapsing of the transverse ribs. 70

Fig. 4 is a vertical section through a one-part bolt anchor known in the trade as an anchor, screw anchor, or ductile anchor.

In the illustrative embodiments of my invention shown in the drawing, 1 is a bolt 75 anchor formed of the sections 2 and 3 which are secured together by the usual clamping lugs 4. These two sections 2 and 3 form an expansion bolt anchor having a body portion or shell 5 of peculiar and distinctive configuration. The bolt anchor is provided with an open throat 6 which is the beginning of the axial bore 7. That portion of the bore which is the open throat is substantially cylindrical. Adjacent to the open 80 throat the axial bore 7 tapers toward the other end of the bolt anchor to a point which is its nearest approach to the axis of the bolt anchor. This point may vary between the ends of the anchor. Preferably it is located 85 at the point 8 which is some distance from the end 9. From this point 8 to the end 9 of the bolt anchor the axial bore is substantially cylindrical.

The body portion or shell 5 gradually increases in thickness from the end 11 of the bolt anchor to approximately the point 12 which is adjacent to the point 8. From the point 12 the portion 13 of the body member or shell 5 is of uniform thickness, but not as 90 thick as the shell is at the point 12.

95 In the form illustrated I mount a series of transverse ribs 14, 14 of uniform height on one portion of the bolt anchor, and another series of transverse ribs 15, 15 of a 100 different uniform height upon the other portion of the body member or shell, both series terminating in a uniform cylindrical

exterior. Upon the collar I mount longitudinally extending ribs 16 which preferably extend slightly above the tops of the ribs 14 and 15.

By this form of bolt anchor having the peculiar contour of body member or shell 5 in combination with the series of ribs 14, 14 and 15, 15, together with the other features, I am enabled to make a bolt anchor of great flexibility and one of light weight, whereby the metal required in its manufacture is economized without impairing the strength of the bolt anchor.

In use a hole 17 is drilled in the support 18 of masonry, brick, terra cotta, tile or any other suitable material and the bolt anchor 1 is placed therein, the work 19 being held to the face 20 of the support by the lag screw 21. When the sections 2 and 3 are cast the female screw threads 22 are cast in them at the same time.

In those cases where a hole 23 is drilled in the support 18 a little too tight or is too small in diameter to accommodate the full expansion of the bolt anchor, the high and weaker ribs 15, 15, all of uniform height, will bend or collapse as shown in Fig. 3 from the point 12 adjacent to the point 8 which is the nearest approach of the inclined axial bore 7 to the axis of the bolt anchor. One or more of the other transverse ribs 14 may also bend or collapse if the strain is sufficiently great. This permits my improved bolt anchor to be used in a hole which otherwise would have to be redrilled or enlarged, or a different size bolt anchor would have to be used.

The maximum strain or grip is distributed by my bolt anchor from a point 19 to the inner end 9 of the bolt anchor. It is therefore impossible to twist off the head of the lag screw if the bolt anchor is used in a hole a little too small to accommodate its maximum expansion, but the body member or shell is also given great rigidity where the axial bore tapers and where the expansion is produced.

My invention may be also embodied in bolt anchors formed of some ductile material as for example lead or an alloy in which the screw cuts its own coöperating screw threads. I have shown in Fig. 4 a one piece bolt anchor 24 formed of lead or an alloy having a body member 25 and an inclined bore 26 and different sets of transverse ribs 115 and 114 and longitudinally extending ribs 116 all of which operate in the same manner as the corresponding elements previously described in full.

Having thus described the invention in connection with different illustrative em-

bodiments thereof, to the details of which I do not desire to be limited, except as required by the scope of the appended claims.

What I claim as my invention and desire to secure by Letters Patent is:—

1. In a bolt anchor the combination of an expansible member having a wall which gradually increases in thickness to a point between its ends and from that point is of less and of uniform thickness to the end of the bolt anchor.

2. In a bolt anchor the combination of an expansible member having a wall which gradually increases in thickness to a point between its ends and from that point is of less and of uniform thickness to the end of the bolt anchor and exterior transverse ribs of uniform height on the respective exterior portions of the bolt anchor.

3. In a bolt anchor, the combination of an expansible member having an axial bore tapering from near one end to a point intermediate the ends of the anchor and from that point being of substantially uniform diameter, the body of the expansible member having a wall which gradually increases in thickness to a point between the ends of the anchor and from that point is of less and of uniform thickness to the end of the bolt anchor.

4. In a bolt anchor, the combination of an expansible member having an axial bore tapering from near one end to a point intermediate the ends of the anchor and from that point being of substantially uniform diameter, the body of the expansible member having a wall which gradually increases in thickness to a point between the ends of the anchor, and from that point is of less and of uniform thickness to the end of the bolt anchor, and exterior transverse ribs of uniform height on the respective exterior portions of the bolt anchor.

5. In a bolt anchor the combination of an expansible member having an axial bore tapering from near one end to a point intermediate the ends of the anchor and from that point being of substantially uniform diameter, the body of the anchor having a wall which increases in thickness approximately throughout the length of the tapering axial bore, said wall from that point being of less and of uniform thickness to the end of the bolt anchor, and two sets of transverse ribs of different height on the exterior of the bolt anchor the ribs in each set being of the same height.

HENRY W. PLEISTER.
